The schedule referred to in the Boston Patent & making part of the same, containing a description, in the words of the said James Wilson himself of his improvement in the construction of the union or double grate connected with flues of various forms & kinds for burning Anthracite & Bituminous coal for Heating Rooms &c.

Wilson, Improved Patent Pyramid Hot-air Guards Plate union or double grate flues for burning all the various kinds of Anthracite coal & all other flammable substances with the greatest economy adapted to all the varieties of situations, such as meeting houses, halls, steamboats, sailing vessels, burning houses, Kitchen Stoves, Cabins &c &c on an entirely new principle never before known or used, in the United States.

Description of Improvement. The four corners of the Stove inside may be formed into hollow squares by means of right angular cast Iron Heaters with triangular Flanges on the inner edge forming projections for receiving the linings entirely preventing them from inclining towards the centre & may be inserted at any time without taking the Stove down, on the surface of which the action of the fire is intense, the linings may be made of clay, soapstone, or any other suitable material of all sizes and kinds, one, two three or four flues may be made at the same time in just various situations, the flues commencing either in the rear of the fire or sides, or a level with grate, below or above, causing the air of the room to pass directly through the fire, thereby giving the greatest possible draft either with or without a blow or damper & consumes all the flammable portions of the air. In the upper part & second chamber of the stove, is a door or damper or valve air tight, which is opened & shut at pleasure to let the smoke & gas pass into the flue in kindling a fire; & when open to cause all the coal to ignite & burn at the same time; & when shut to stop ignition above the opening in the flue below the cast iron plate or door-lid box in connection with the clay lining. The glass of the

plates connected with the back or side of the stove, may be square, ^{long} round, half circle, one fourth or one eighth of a circle, or any other shape or figure that will preserve an open cavity between the surface & guard plates, which are destined to receive the violence of the fire & prevent injury to the outside plates or in the least diminishing their beauty. There are openings in the outside plates back of the door to admit a free circulation of cold air which is heated by means of the guard, dovetail plates or for & then passes freely into the room; or it may be constructed by adding a hollow tube passing round the inner surface of the stove receiving the heated air from the arched flues at the four corners of the stove or hollow square, or any form of heater; it may then be conducted to any apartment of the building heating with the same any portion or portion of the same with less expense in fact than any thing heretofore known or used. The fronts of the different forms & sizes of the above described stove, may be open, giving the most beautiful fire, equal to the most approved parlor grates & retaining the same economy as the stove above mentioned, having an open fire, with a door or brazier in the form of a window-pane resting on hinges or suspended in any other way & may be removed at pleasure, retaining when in its place all the advantages of those left open by filling the spaces with mea through which the rays of light may be emitted. The door may be of any size from a platter, the most approved in an oblong square or round with one or more staves, with arms or spear tips, the hinges may in both cases be of iron or clay, which is detached with arched flanges to receive the clay or iron with the iron. Description of the union or double gate which is made in two parts of cast or wrought iron or any other suitable materials, the one half of the bar or connected to the shaft on the centre on which the gate when pointed with the other half rests, is made a part of the same by fastening either of screws or pins, or by another means of uniting them firmly together, & yet permit the gate shaft to vibrate in the outer groove that passes through the side or post, or is separate from the main shaft, receiving the latter in means of a hollow square resting on a collar made fast to the side

by screws or nuts to be removed with ease, in order to insert or remove the grate, without taking the stove, in pieces, by a crank on the side of the stove ~~as~~ may be used in front with a lever or any other purchase sufficient to detach the ashes from the coal & drop them into the ash pit attached to the shaft by which being moved one fourth of a circle, the coal will be agitated the whole length of the grate at once & the ashes be caused to drop into the pan below, without pulverizing or wasting the coal as is the case with most other grates by removing the fastenings to the frame part of the grate the whole contents of the chamber of combustion is made to drop into the pan below, by giving the crank a motion equal to one fourth of a circle, as it may be suspended on centres in the form of a right angle, the bars of the grate may be flat or concave.

Summary. I claim as my invention first the union grate as be-

... You described, also the manner of discharging the same by describing the quarter of a circle or any segment thereof, or by means either of a swing or drop grate, the bars having been made for containing fuel or discharging it by one motion into the ash pan, setting on the centres with or without half circle, triangular or concave bars, the latter being greatly preferred for the convenience of moulding the same being lighter & stronger than the half circle, oblong, or any other form. Second. I claim as my invention the opening in the sides or outer surface of the stove for the admission of air to prevent the iron box or guard plates from being destroyed by the intensity of heat from antifuse or other coal. Third. I claim as my invention & improvement the movable damper or valve sliding under ovens to prevent extra heat from direction to the funks of heat & passing the same up the extra a back flue, at or near the bottom or at the junction of the upper outlet, through the body of the stove, into the back flue or chimney; giving perfect direction to the fire entirely preventing by closing the damper or movable plate, the surplus heat so much complained of in all other stoves henceforward, without the damper casting

guard plates on top. (Continued) I claim as my invention the cast iron guard plates or bars, either round or square or any other form, which are separate from the sides or back of the fire, & make a part of the same by being separate & fastened either by screws, part or in any other way, so as to make the same an tight, ^{which may be of a circular form or} any segment of a circle, & which when united to the sides or back, will form an open cavity for the circulation of air to take in the heat in the room, without destroying the guard plates or bars; and prevent any injury to the surface plates, as well as keep any thing from burning that may chance to come in contact with the outside of the stove, & also preserving the same beautiful surface as the other plates. Also in connection with the above described movable plate or damper. I claim the upper damper in the chamber of combustion to let off the smoke & gas in making a fire, & to cause the whole content of the stove to be ignited at the same time if desired. The chamber of combustion may be made a part of the said stove or separate, so as to be removed at pleasure & of any form or size desired, observing that the same be made an tight that combustion may be prevented when the damper is closed. The hopper or bin may be made large enough to contain a sufficient quantity of fuel, to keep up combustion for days if required by raising or lowering the tube made of iron, clay or brickstone, of any form & suitable size to discharge the coal at or near the grate, preserving a sufficient distance from the floor or grate of the furnace to graduate the quantity of coal to be consumed to any degree of heat wished for. By means of the tube less than one quart of nut coal can be made to burn & the consumption of fuel confined to any given quantity by raising or lowering the same & thus regulating it at pleasure. By one part of the tube being movable sliding upon the outer or inner surface of the main tube connected with the hopper, receive a bin, which may be raised or lowered to increase or diminish the quantity of fuel to be consumed, observing at the time of using the tube to keep the upper damper in the chamber of combustion closed to prevent the air

from passing through the tube if possible; which can be effected only by having the valve a damper airtight & keeping it constantly closed, especially in the use of the fire or smut coal & when combustion is designed to be kept up for a length of time without replenishing the fuel, & the hopper or reservoir may be sufficient in size to keep up any given temperature for days. The same construction of hopper is described in the written specification except that the feeders are on the outside of the furnace instead of the centre or inside in order to increase the quantity of fuel to last a length of time if required to keep up the fire without constantly changing the same as in the case with all other furnaces now in use. By which means three or nine kinds of coal can be injected to any given point below the mouth of the furnace or cupola, to wit, charcoal in the lower part, coke or Liverpool in the centre, & anthracite at the top or mouth; or any other suitable material can be used. The ore or metal to be melted is suspended over the top of the furnace or cupola in a hopper or reservoir to receive the fuel from the top of the furnace heating & drying the ore the better preparing it for the furnace or cupola, as it diminishes the quantity of fuel; gives greater facility in fusing & melting; & producing greater uniformity in the quantity of the ore. By the aid of machinery attached to the hopper at the top of the furnace, the ore can be kept constantly discharging from the hopper into the top of the furnace, & the supply increased or diminished to supply the wants of the furnace, working fast or slow. The same constructed hopper or reservoir can be used in or on the outside of any stove for culinary purposes as well as for the purposes above & may be made of any suitable material either sheet or cast iron, copper, tin or of any other substance that may answer.

N.1 Improvement in the management of heat, as applied to cooking stoves of every form & kind, for all culinary purposes, in the use of wood or coal, in applying the same to the oven & boiler in the most economical manner, never before known or used, without the usual destruction of the oven plates & dampers, sliding under or

872 X

surrounding outside of said oven, giving a more perfect convection to the flame conveying it to the entire outside of the boiler, increasing I diminishing the quantity of heat by sliding the guard plate sliding under the oven from 0 to 10 inches, the same to be moved at pleasure or remain stationary, to ext. the part of heat in the oven for baking boiling, roasting or any other purpose. the above guard plate resting on flanges cast on the inner coverage of the side oven plate sufficient distance from the bottom oven plate to stop all the flame, or flames of heat between the guard plate & the bottom oven plate if required or any part of it, the guard plate giving perfect convection to impeding any portion of fire for the purpose above named, by means of a thin wire passing through the outside of the stove, or may be used by any other suitable instrument resting on or between the flanges cast on the under side of the guard plate for that purpose, near the front lower side the same sliding damper is used, putting sheet of copper directing the fire to & from the sheet, in its passage in the sheet or tube of having avoided the great inconvenience of the former plan & expense of the former sliding damper under the ovens of cooking stoves, its destruction by intense heat to which they were exposed & the manner they were made to act under the oven, have substituted the following sliding or revolving damper, resting on a wide flange cast on & making a part of the upright side oven plate from one to six inches, more or less, at right angles, with the upright side oven plates, themselves forming an impenetrable guard plate to the dampers sliding or revolving on the upper side of the same the fire passing under the guard & projecting wing of the upright side oven plates, the said projecting part of said plate to extends to nearly the outer surface of the stove conveying the flame or flames of heat to the outside of the boiler, thereby consuming much less fuel than any other stove of like construction known or used before, & by means of steps cast on the sides of the stove to receive the dampers as it revolves, any given quantity of heat may be applied to the boiler by its motion if required, and by

Leaving the fire under the surface of the projecting wing of the upright side oven plate is heated more effectually than formerly, with great economy in carrying the flame or flames from the furnace cans to the outside of the boiler, the same right angle plate cast out & making a part of the top or bottom oven plate, to all kinds of coal stoves plate, such as iron bottom back, &c, when the action of the fire is confined to a certain or small portion of the plate, moveable curve plate forming at pleasure an inclined plane to carry the coal from the feeder to the side near the front of stove. the improvement herein described consists, first, in the raising or placing guard plate cross or lengthways of the oven in cooking stoves on flanges cast on the inside upright oven plates one or more inches below the bottom of oven leaving sufficient space to pass the flames & puffs of heat between the oven plate & damper, the heat to the bottom & diminishing it at pleasure by the motion of the plate from two to four inches from front to rear under the oven, the same damper is used in turning off fire. connected with said upright side oven plate is a right angle or wings cast out & making a part of said side oven plates, upon which the sliding damper rests on the upper side of the plates saving the damper from injury by fire as heretofore, giving direction to the fire to the outside of the boiler, consuming much less fuel & securing a regular degree of heat to the oven not before known or used.

Having recently discovered by various experiments that cast iron plates upon which the fire acts upon a part of the surface is soonest from breakage by turning it the thickness of the plate ^{into} the bottom of all kinds of stoves for cooking 189 plate iron stoves, bottom, all fire plates & back to Franklins, heat face with straight or level plates, by turning them are entirely prevented from breakage by fire as heretofore, the same right angle plates are attached to the top & bottom oven plate & forming an entire fire plate in front of all coal or wood cooking stoves, gives additional heat to the top & bottom oven plate in baking or piping.

Having discovered the great advantage in burning anthracite coal in all Pyramid stoves, of all sizes & forms especially the oblong square

by attaching the same to the boiler, from the top, in channels, so as to stand upright, and leaving them for the purpose of forming a check to the circulation of water to be heated, so as to put the consumption of fuel to a minimum, preventing the metal of the plates, from overheating, recently made, have also had a new plan, &c, in the formation of all cast iron plates, where the action of the fire is intense, or any part or section of it, is not all of the same, as, such as might bottom to cook stoves, by carrying the surface of the same at least the thickness of the plate by expansion of metal, to a convexity, returns a gas-tight, firm, state without breakage, & without injury to the plates, back to Franklin, & all other cast plates, exposed to part to the action of the fire, heat, &c, made with a flat or straight surface are not made convex, in order to prevent breakage as here before.

Similarly

No. 3 I claim as my invention improvement, the invention of guarding the iron of all sliding plates from burning at bottom by a stationary or movable plate, under iron for all ordinary purposes, giving any portion of heat to the same, in baking, firing, &c. No. 3 I claim as my invention improvement, the flange is in the shape of eight angles, with the upright side iron plate, extending outward, from one to six inches, more or less, to carry the fire to the outside of the boiler, & to provide for the heating of the upright part of said side iron plate, by the action of the fire upon the surface of projecting part of said plate, the red hot damper resting on the same, preventing its destruction by fire. No. 3 I claim the application of said flange, guard plate in connection with a number of inclined plates, iron or any other formed plate, for turning sheets of paper, thereby, regulating the action of the fire to the same at pleasure. No. 3 I claim as my invention improvement, the guard of projecting plates, making a flat bottom or top, over to upright side iron, as above, giving, in entire, new protection to the sliding or moving guard plates, warmer, keeping the same from the usual destruction by the action of the upper, surface, shielding the same.

from fig. 5th I claim as my invention & discovery the forming
from breakage all stones or cast iron plates by cutting the same
at least the thickness of the melting of the outer surface plate
of each union by opening the sides of the plates in the bottom
of top plates.
